UNITED STATES PATENT OFFICE

136,046

DESIGN FOR A BUTTER MEASURE

Katherine R. Downer, Villa Nova, Pa.

Application March 27, 1943, Serial No. 109,833

Term of patent 7 years

To all whom it may concern:

Be it known that I, Katherine R. Downer, a citizen of the United States, residing at Villa Nova, in the county of Montgomery and State of Pennsylvania, have invented a new, original, and ornamental Design for a Butter Measure, of which the following is a specification, reference being had to the accompanying drawing, forming part thereof, in which:

Fig. 1 is a perspective view of a butter measure showing my new design; and

Fig. 2 is a perspective view thereof in inverted position.

I claim:

The ornamental design for a butter measure, as shown.

KATHERINE R. DOWNER.
